UNITED STATES PATENT OFFICE.

CHARLES E. SKAGGS AND BYRON E. LOGAN, OF BAY POINT, CALIFORNIA.

RAILROAD JOINT.

Application filed June 14, 1927. Serial No. 198,775.

The invention forming the subject matter of this application relates to railroad joints.

An object of the invention is to provide a railroad joint in which the joint is formed by the ends of the rails themselves without necessitating any bars to reinforce the same.

Another object of the invention is to provide identically beveled rail ends which form an uninterrupted continuity of rails and which are substantial and strong enough to prevent the separation of the rails, but permit sufficient clearance between the rail ends to provide for the expansion of said rails.

A still further object of the invention is to provide overlapping rail ends which are adapted to carry the same or more load than any of the present rail joints in use and which eliminate the use of the reinforcing plates such as fish plates.

The above and other objects in view will more readily appear as the description proceeds.

Although we show and describe a preferred form of the invention it is to be understood that changes as to the form, parts and arrangements thereof may be made within the scope of the claims, without departing from the spirit of or sacrificing any of the advantages of the invention.

In the accompanying one-sheet of drawings,

Figure 1 is a perspective view of the rail joint,

Figure 2 is a perspective view of one of the rail ends,

Figure 3 is a section taken through the approximate horizontal center line of the rail joint,

Figure 4 is a cross section taken along the line 4-4 of Figure 3.

In carrying out our invention we provide rail ends 1 and 2 shown in Figure 1, said rail ends to be identical, therefore the description of one of said rail ends explains the design and the function of both rail ends. The rail end 1 is beveled from the point 3 to the end of the rail. Along the central portion of the beveled end, the inner surface thereof is straight from the points 4 to the end of an extension 5. Said straight face of the extension 5 is in alignment with

the outside face of the web 6 of the rail. In order to provide sufficient material to reinforce the end of the rail cut in said beveled shape a web flange 7 is provided extending from the end of the extension 5 to substantially inside of the point 3. The outside face of said web flange 7 is parallel with the outside face of the web 6, thereby providing increasing reinforcing thickness from the end of the extension 5 to beyond the other end of the bevel cut. Squared shoulders 8 and 9 are cut respectively on the base flange and head flange of the rail at approximately the end of said bevel in order to form an abutting surface for the ends of the adjoining rails. Elongated holes 10 are spacedly disposed in the beveled end of the rail to receive bolts 11 holding the opposite rail ends together. Although the bevel extends on the rail to the shoulders 8 and 9 the horizontal central portion thereof from the points 3 is cut straight in a line with the inside surface of the web 6 thereby forming an indentation therein to receive the extension 5 of the other rail. The inside surface of the extension 5 is straight from the points 4, said points 4 being inside of the end of the rail. Thus the extension 5 protrudes from the face of said bevel said protrusion to correspond with the indentation on the opposite end of the bevel, as it is clearly shown at 12 on Figure 4.

The forming of a railroad joint now involves simply the sliding of the beveled portions of the rails together so that the extensions 5 slide into the indentations on the bevels and the elongated holes 10 are brought in registry with each other so as to permit the bolts 11 to be passed therethrough. After the bolts are tightened up a firm joint is formed and the ends of the rails are prevented from moving up or downwardly relative to each other because of the extension 5 and the indentation in the bevel. The longitudinal slipping of said rails is permitted only to the extent of the possible expansion of the rails.

The advantages of the invention consist in reducing the number of working parts and the simplicity of the assembling of a joint. The strength of the railroad joint heretofore described stands up under any circumstances and eliminates all parts which may work loose under heavy duty.

Having thus described our invention, what we now claim as novel and desire to secure by Letters Patent is:

1. In a rail comprising a base flange, a web, and a head flange, aligning shoulders squared on one side of said head flange and base flange and disposed at a distance from the end of the rail; a longitudinally tapered face extending from said shoulders to the end of the rail and on one side thereof, a reinforcing flange on the side of said web opposite to said tapered face and extending beyond the end thereof, said end being adapted to receive means for securing the same to a complementary end of another rail on said tapered face, the tapering of the web terminating inside of the ends of the tapering of said head flange and base flange; a face substantially the width of said web and substantially parallel with the reinforcing flange extending in continuation of said tapered web face to the extremity of said reinforcing flange, thereby forming a protrusion on said tapered face having continuations of said tapered face on either side of it to the end of the rail, another straight surface extending in continuation of the inside end of said tapered web face, forming

a complementary indentation at said inside end of said tapered web face and between 30 said head flange and base flange.

2. In a rail comprising a base flange, a web, and a head flange; aligning shoulders squared on one side of said head flange and base flange and disposed at a distance from 35 the end of the rail; a longitudinally tapered face having head and base portions and a web portion; said head and base portions of said tapered face extending from said shoulders to the end of the rail, said mediate 40 web portion of said tapered face being shorter than said head and base portions, the extremities of said mediate web taper being equidistant from said shoulder and said rail end; the unreduced mediate web 45 portions in continuation of said web taper forming a protrusion in the nature of a wide rib extending gradually from the surface of said tapered face at the thin end and a complementary indentation at the thick end of 50 said reduced face.

In testimony whereof we affix our signatures.

CHARLES E. SKAGGS.
BYRON E. LOGAN.
